UNITED STATES PATENT OFFICE.

JOHANNES LOOSE, OF STUTTGART-CANNSTATT, GERMANY, ASSIGNOR TO THE FIRM OF FORTUNA-WERKE, SPECIALMASCHINENFABRIK, G. M. B. H., OF STUTTGART-CANNSTATT, GERMANY.

PULLING-OVER MACHINE.

1,172,616.

Specification of Letters Patent. Patented Feb. 22, 1916.

Application filed February 16, 1915. Serial No. 8,697.

To all whom it may concern:

Be it known that I, JOHANNES LOOSE, of 31 Karlstrasse, Stuttgart-Cannstatt, in the Kingdom of Wurttemberg, German Empire, 5 civil engineer, have invented certain new and useful Improvements in Pulling-Over Machines, of which the following is a specification.

My invention relates to machines used 10 in the manufacture of shoes for pulling over the upper leather on the last, and its object is to provide a machine of this kind which is both effective in use and easy to handle so as to allow the operator to work 15 quicker and with more safety and to accomplish better results than with other machines designed for the same purpose.

To this end the invention consists of the machine and of the combination of parts 20 therein as hereinafter described, and more particularly pointed out in the claims at the end of the specification.

The machine according to the invention 25 consists of a device for mounting the last, said device being adapted to be turned around a horizontal axis and being provided with a system of pliers adapted to be displaced vertically and designed to pull the upper leather tightly over the last.

30 In the drawings accompanying this specification Figure 1 is a side elevation, partly in section, of the machine. Fig. 2 is a detail of the mechanism used for turning the last mounting device, the parts of said mechanism being in positions corresponding to the positions of parts shown in Fig. 1; Fig. 3 is a side view, on a larger scale, of the pliers employed to pull the leather over the last; Fig. 4 is a rear view of the pliers.

40 In the hollow standard *a* a hollow horizontal shaft *b* is rotatably mounted in suitable bearings, and carries the parts *c*, *d* for mounting and fixing the last *e*; and the devices for pulling the upper leather over the last. These latter devices are fixed to one end of shaft *b* and comprise a row of pliers *g* adapted to be closed and pulled downward 45 by the action of a gliding piece *i* operated by means of a hand wheel *o*.

50 The pliers are controlled by a pulling string or chain *h*', common to all of them, said string being conducted over a pulley *y* and two rows of pulleys *s z*, the pulleys *z* being fastened to a support *f* carried by the

hollow shaft *b*, while pulleys *s* are mounted 55 on the gliding piece *i* and within bearings provided between the shaft *b* and the support *f*. A rack *k* on said gliding piece gears with a pinion *l* on a shaft *l'* located in the hollow shaft *b* which may be rotated by 60 means of a miter wheel gearing *m n* and a hand wheel *o* connected with it. By turning the wheel in one direction shaft *l'* is rotated and the gliding piece *i* is lowered, thereby pulling the pliers *g* downward. A 65 pawl-coupling *p q* serves to retain the gliding piece *i* in position, the ratchet wheel *q* being fixed to shaft *l'*, while the pawl *p* is pivoted to a disk *r* fastened to the hollow 70 shaft *b*. Disk *r* is provided on its circumference with two notches *w* disposed diametrically opposite each other. Immediately below disk *r* a rod *u* is arranged within the standard *a*, the lower end of said rod being connected to a treadle *v*, while its upper end *t* is forced by a spring *u'* upward against the circumference of disk *r* and into one of the notches *w*. By depressing foot-lever *v* the rod *u* is drawn downward thereby removing the upper end of rod *u* from 80 notch *w*. The result is that pawl *p* is permitted to swing on its pivot into engagement with the teeth of ratchet wheel *q*. A disk *r* moves on its axis, the last *e* together with its support swings about the journal *l'*. 85 This continues until the upper notch of disk *r* arrives at its lowermost position and stands in line with the end *t* of rod *u*. The foot-lever *v* being released the action of spring *u'* moves rod *u* upward and the end *t* 90 enters the notch which was formerly presented upwardly but is now presented downwardly. Inasmuch as the support has been turned 180° pawl *p* is retained in engagement with the ratchet while the nails are being driven. After a shoe is completed, the support is turned 180° into its old position. Here the lock is released, the tension cord is loosened, and the claws relaxed so that the shoe can be taken away and a new one 100 inserted. As soon as the foot-lever *v* is released, the last support is locked in its position, whereas the claw system is freed.

In the upright position shown in Fig. 1 the last *e* is ready for mounting and to have 105 the upper leather pulled tight thereon by means of pliers *g*. Upon the treadle *v* being actuated the end *t* of rod *u* is withdrawn

from the notch *w* of disk *r*, when by turning the hand wheel *o* in one direction, the shaft *b* is coupled with shaft *l'* by means of claw-coupling *p q*. Thereupon the support *f* which carries the last as well as the pliers, is turned upside down, thus assuming the position most suitable for pegging, the end *t* of rod *u* being then forced back by the spring into the opposite notch *w* of disk *r*.
 10 By turning the hand wheel in the opposite direction shaft *b* and disk *r* are uncoupled and the support *i* is lowered and the pliers *g* are pulled downward. As shown in Fig. 2, the upper end *t* of rod *u* is in contact with the free arm of pawl *p* whenever it has entered a certain one of the notches *w*, and serves to hold the pawl away from the ratchet wheel.
 15

The pliers which are used for pulling the leather over the last are shown in Figs. 3 and 4. They comprise a jaw 1 at the end of a forked arm 2 and a counter-jaw 3 at the end of a short arm 4 provided with a projection 5 at its inner edge. An arm 8 pivoted on the pivot of the pliers carries a pin 7. A pawl 6 pivoted on said pin 7, cooperates with the projection 5 on arm 4, and is held in contact with it by a spring 9. Said pawl can be disconnected from projection 5 by a pulling string 10. The arm 8 is controlled by the pulling cord or chain *h* mentioned above. A spring 11 pressing against arm 4 tends to keep the pliers open; a spring 12 serves to press arm 8 against arm 2.
 35

The operation of the pliers is as follows: The arms 4 and 8 are grasped between two fingers, thus causing jaw 3 to grasp the lower edge of the upper leather and to press it against jaw 1 as tightly as possible, the pawl at the same time entering the recess formed by the projection 5 on arm 4. Now the cord or chain *h* is pulled downward in the manner described above, thereby pulling the upper leather tightly over the last. The pull exerted on the cord *h* not only causes the pliers as a whole to move downward, but also the jaw 3 to be pressed tightly against jaw 1, the pull being exerted upon arm 4 through the medium of arm 8, pawl 6 and projection 5. When the operation of pulling over has come to an end, there is no need for discontinuing the pull exerted upon cord *h*; by pulling the string 10 the pawl 6 is disconnected from arm 4 and the jaw 3 is forced into the open position by spring 11. This arrangement is especially useful in the quick removal of the leather from the last and in displacing single pliers without being compelled to move the others.
 60

The pliers are fastened to part *f* of the machine by means of bolts fixed to the machine and projecting through the slots of the forked arms 2 of the pliers. As shown in the drawings the arm 2 of the individual

pliers is guided by two horizontal screw threaded bolts *v' w'* provided with setting screws 21, 22, 23. The screws are preferably set in such a position as to hold the jaws of the pliers a short distance back of the edge of the last and to allow them to execute a movement of oscillation toward the standard *d* under the action of cord *h*. The uppermost pulleys *y* serving to guide the pulling cords *h* are located behind the pliers in order to render the movement of oscillation possible. The lower end of each cord *h* is fastened to the axle of a pulley *z*, and a pulling string *h'* common to all the pulleys *z* is acting upon them in pulley block 80 fashion.

Preferably the bolts *v' w'* are fastened to a vertical pivot in order to render them easily movable in a horizontal direction.

I claim:—

1. In a pulling-over machine a horizontal shaft, a last support thereon, a row of pliers disposed on said support, tensioning means for said pliers, means for turning the support on said horizontal shaft, a driving wheel at one end of this shaft for tightening said tensioning device, driving wheels on the other end of said shaft, means for coupling the turning and tensioning means, and means for releasing the coupling between the turning and tensioning means.
 85

2. In a pulling over machine, in combination, a last support, a plurality of rows of screw threaded bolts arranged on said support, one above the other, and pliers movably mounted in a substantially vertical position on said bolts.
 90

3. In a pulling over machine, in combination, a last support, a plurality of rows of screw threaded bolts arranged on said support, one above the other, stops and set screws on the lower row of bolts, set screws on the upper row of bolts, pliers movably mounted in a substantially vertical position on said bolts and between the stop of the lower bolt and the set screws on the bolts, and means for operating the pliers.
 105

4. In a pulling over machine, in combination, a last support, a row of pliers movably fastened to said support by one arm each, intermediate arms pivoted to the pivot pins of said pliers, pawls pivoted to said intermediate arms, projections on the free arms of said pliers opposite said pawls and means for disengaging said pawls from said projections.
 115

5. In a pulling over machine, in combination, a last support, a row of pliers movably fastened to said support by one arm each, intermediate arms pivoted to the pivot pins of said pliers, pawls pivoted to said intermediate arms, projections on the free arms of said pliers opposite said pawls, springs adapted to open said pliers and to keep said pawls engaged with the projec- 125
 130

tions on said free arms, springs adapted to press said intermediate arms toward the fixed arms of said pliers, means for pulling said intermediate arms backward and downward in the direction of the fixed arms and means for disengaging said pawls from said projections.

In testimony whereof, I affix my signature, in presence of two witnesses.

JOHANNES LOOSE.
